UNITED STATES PATENT OFFICE.

WILLIAM DRAPER, OF WAVERLY TOWNSHIP, CHEBOYGAN COUNTY, MICHIGAN.

DART.

1,289,702.

Specification of Letters Patent.

Patented Dec. 31, 1918.

Application filed February 6, 1917. Serial No. 146,968.

To all whom it may concern:

Be it known that I, WILLIAM DRAPER, a citizen of the United States, residing at township of Waverly, in the county of Cheboygan and State of Michigan, have invented new and useful Improvements in Darts, of which the following is a specification.

The present invention relates to projectiles, and more particularly to that class thereunder known as darts primarily adapted for conveying inflammable explosives, thus providing a dart which will ignite and scatter its contents by the impact or force of the same against the target.

A further object of the invention resides in the provision of a dart so constructed to adapt the same to discharge a plurality of smaller projectiles and the firing of the said projectiles being simultaneous.

Furthermore, I contemplate in providing a dart which is so constructed as to render the same efficient in use and one which is simple and durable in construction and may be manufactured and sold at a minimum cost.

With the above and other objects in view, the invention consists in the novel features, details of construction and combination of parts which will hereinafter be more fully set forth, illustrated in the accompanying drawing and pointed out in the appended claims.

Figure 1 is a perspective view of the dart; and

Fig. 2 is a vertical section.

Referring more particularly to the accompanying drawing, in which like characters of reference refer to corresponding parts in the several views, 5 denotes the dart generally which is preferably formed of brass, other metal or the like material and adapted primarily for use by aviators. The dart 5 in this particular instance is shown as consisting of an upper hollow cylindrical casing 6 and a lower frusto-conical casing 7, the lower casing being connected with the upper casing through the employment of a coupling 8. Suitable means are employed for connecting the upper casing 6 to the coupling 8 which in this particular instance is shown as comprising rods 9 projecting through the apertures of the annular flange 10 and threadedly engaging as at 11 in said coupling, thereby establishing a firm connection of the casing to said coupling.

Screws or the like fastening devices indicated by the character 12 are utilized for connecting the upper end of the lower casing 7 to and in embracing relation with the lower end of the said coupling 8. The upper section 6 of the dart is primarily adapted to be utilized as a tank for containing a predetermined quantity of inflammable material indicated by the character 13, of liquid form, such as gasolene, or the like, and the purpose of this tank is to serve as a torch for the dart. The coupling 8 is provided throughout its vertical axis with a passageway 14, while the character 15 indicates a series of internally threaded sockets into which the inner ends of the radially extending barrels 16 are threaded and each of the barrels 16 is adapted to contain a cartridge 17. A tube 18 is mounted in the upper end of the passageway 14 and projects within the cylinder 19 formed internally of the upper casing 6 and is adapted to contain a predetermined quantity of powdered explosive substance, denoted by the character 20. A cartridge chamber 21 is secured to the bottom of the coupling 8 by means of the fasteners 22 to vertically aline the same with not only the passageway 14 but likewise with the tube 18 for a purpose to be hereinafter set forth, and carried in this cartridge chamber 21 is a firing cartridge 23 carrying a projectile 23'. Secured within the coupling 8 at a point slightly above the cartridge chamber 21 is a cluster of upwardly and inwardly inclined yieldable fingers 24 with which contacts the inner extremity of the firing pins 25 utilized in firing the cartridges 17 from the barrels 16. The pointed nose 26 is connected beneath the lower casing 7 by a hollow tube 27 containing a quantity of explosive substance, and such tube projecting through the closed end wall 27' and axially within the lower casing 7. In the enlarged open upper end of the tube is located a cap 28 while fitted over the upper end of said tube is a percussion plunger 28. A tank 29 adapted to contain a quantity of liquid inflammable substance is secured within the lower casing 7 and in embracing relation with the tube 27, and contained within the tube 27 and the extreme lower end of the lower casing 7 is a quantity of powdered explosive material in the form of dynamite or the like denoted generally by the character 30, and the explosive substance, that is, that portion thereof con-

tained in the lower end of the lower section 7 is exploded by the aviator preferably by igniting the upper extremities of the fuse 31 after the same have been released from 5 the hooks 32 and projected through the openings 33 formed in the lower casing 7. At this point, it might be stated, however, and as will be more fully set forth as the 10 description of the invention is proceeded with, upon the striking of the nose 26 against a fixed object such as a fortification, bridge, ship or building of the like character, the impact of the dart will tend to explode the dynamite and the pointed nose 15 26 in turn will penetrate the object or structure aimed at. This latter referred to firing operation of the powdered substance or dynamite contained in the lower end of the lower casing 7 is assisted due to placing 20 therein caps denoted by the character 34, and furthermore, communication between the tube 27, caps 34 and container 29 is accomplished through the employment of a fuse 34. In order to prevent any accidental 25 firing operation of the dart, until the proper time, and that the dart may be held in firing position, use is made of a safety device indicated generally by the character 35 including a removable L-shaped ring 36 and 30 a fixed annular ring 37. The horizontal portion of the removable ring 36 abuts with the upper surface of the nose 26 and holds the lower end 27' of the lower casing 7 in an elevated position in the cavity 38 of the 35 nose 26 until the aviator sees fit to drop or discharge the dart.

In the practical use of the invention, so far as the description of the invention has been stated, the L-shaped band 36 is first 40 removed from the dart, and upon the striking of the dart against the object aimed at, will cause the nose 26 to slide to a distance to receive within its socket 38 the lower end 27' of the dart, such operation causing 45 the operation of the firing pin 38' located in the lower part of the cartridge chamber, on impact by engagement with the percussion plunger 28. The projectile carried by the firing cartridge will spread the cluster 50 of fingers 24 which in the next step of the firing operation of the dart will cause the firing of the cartridges 17 from the radially extending barrel 16 and simultaneously with which, due to the firing cartridge 23 striking 55 the firing pin 39, will cause the ignition of the powdered explosive substance 20 contained in the cylinder 19 and in turn ignite the liquid inflammable substance 18 contained in the upper section 6 of the dart.

Surrounding the lower section 7 of the dart at a point slightly below the point of location of the firing cartridge 23 therein, is a guard 40 of substantially concavo-convex formation in cross section. This 65 guard 40 is in the nature of a collar con-

structed of any suitable material and primarily adapted to explode or discharge the dart upon the striking of the latter within soft bodies, such as water, nets or the like. To this end, the guard 40 is slidably associated on the lower casing 7 of the dart and connected with the extreme upper end of the nose 26, through the medium of a frame 41. This frame 41 embodies a collar 42 embracing the lower casing 7 and having guide 75 openings 43 for slidably receiving the spaced series of rods 44 disposed lengthwise of the said casing and connected at their lower extremities with the nose 26 and at their opposite or upper extremities with the guard 40. 80

From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device 85 shown is merely illustrative, and that such changes may be made when desired as are within the scope of the appended claims.

What is claimed as new, is:—

1. A dart embodying a sectional casing, 95 each section adapted to contain a quantity of explosive material, a coupling for connecting the sections together, a plurality of barrels connected with the coupling, and a firing cartridge connected with the coupling 100 for exploding the cartridges in the barrels simultaneously upon the striking of the dart against an object.

2. A dart embodying a sectional casing, each section adapted to contain a quantity 105 of explosive material, a coupling for connecting the sections together, a plurality of barrels connected with the coupling, a firing cartridge connected with the coupling for exploding the cartridges in the barrels simultaneously upon the striking of the dart 110 against an object, and means for holding the dart in firing position.

3. A dart embodying a sectional casing, each section adapted to contain a quantity 115 of explosive material, a coupling for connecting the sections together, a concentric series of barrels radially extending from said coupling, a firing cartridge connected with the coupling for simultaneously exploding the cartridges of each barrel and also for igniting the explosive substance contained in each of the casings.

4. A dart embodying a casing containing a quantity of explosive substance, a firing 125 cartridge contained therein, and means slidably associated with the casing for causing the explosion of the firing cartridge upon the striking of the same against the target aimed at, and means slidably mounted on 130

- the casing for exploding the firing cartridge upon the striking of the same with a soft substance.
5. A dart embodying a casing containing a quantity of explosive substance, a firing cartridge contained therein, means slidably associated with the casing for causing the explosion of the firing cartridge upon the striking of the same against the target aimed at, means slidably mounted on the casing for exploding the firing cartridge upon the striking of the same with a soft substance, and means slidably mounted on the casing and having connection with the latter mentioned means for exploding the firing cartridge after the striking of the dart against a soft substance.
6. A dart embodying a sectional casing, each section having a quantity of explosive substance contained therein, a nose, a member connected with the nose and extending upwardly within the casing, a firing cartridge, and a percussion cap mounted on the said member for causing the explosion of the firing cartridge to cause a simultaneous explosion of the explosive substances of the casing upon the striking of the dart against an object.
7. A dart embodying a sectional casing, each section adapted to contain a quantity of explosive substance, a coupling interposed between the confronting ends of the sections for connecting the sections with one another, a series of barrels carried by said coupling, a firing cartridge having a projectile connected with the coupling, means slidably associated with the casing for causing the projectile to pass axially through the coupling, and means arranged in the path of movement of the firing cartridge for causing the latter to explode the cartridges contained in the barrels of the coupling.
8. A dart embodying a sectional casing, each section adapted to contain a quantity of explosive substance, a coupling interposed between the confronting ends of the sections for connecting the sections with one another, a series of barrels carried by said coupling, a firing cartridge having a projectile connected with the coupling, means slidably associated with the casing for causing the projectile to pass axially through the coupling, and means arranged in the path of movement of the firing cartridge for causing the latter to explode the cartridges contained in the barrels of the coupling, and a safety device for holding the said slidably mounted means against any accidental movement.
9. A projectile having a plurality of bores, auxiliary projectiles in said bores, a firing pin associated with each of said auxiliary projectiles, a single firing member to directly and simultaneously actuate a plurality of said firing pins, thereby discharging the auxiliary projectiles, and an explosive charge fired directly by said firing member. 65
10. A projectile having a plurality of bores, auxiliary projectiles in said bores, a firing pin associated with each of said auxiliary projectiles, a single firing member to directly and simultaneously actuate a plurality of said firing pins, thereby discharging the projectiles, an explosive charge adapted to actuate said firing member, and impact means to directly ignite said explosive charge. 75
11. A shell comprising a body, cartridges carried thereby, an expandable member adapted for firing said cartridges, a charge for expanding said member, and means for exploding said charge. 80
12. A shell comprising a body, cartridges carried thereby, an expandable member adapted for firing said cartridges, a charge for expanding said member, and contact means adapted for exploding said charge when the shell strikes an object. 90
13. A shell comprising a body having a longitudinally extending bore or chamber, and an expandable member contained within said chamber, cartridges carried by the body, firing pins for the cartridges, said pins being adapted to coöperate with the member, and means for expanding said member to fire the cartridges. 95
14. A shell comprising a body having a longitudinally extending bore or chamber, an expandable member contained within said chamber, cartridges carried by the body, firing pins for the cartridges, said pins being adapted to coöperate with the member, and contact means carried by the shell adapted to expand the member when the shell strikes an object. 100
15. A shell comprising a body having a longitudinally extending bore or chamber, an expandable member contained within said chamber, cartridges carried by the body, firing pins for the cartridges, said pins being adapted to coöperate with the member, and an explosive charge for expanding the member and contact means arranged and adapted to explode said charge when the shell strikes an object. 110

In testimony whereof I affix my signature.

WILLIAM DRAPER.
